UNITED STATES PATENT OFFICE.

WILLIAM SCHNEKENBURGER, OF DETROIT, MICHIGAN.

WEATHER-STRIP.

1,352,545.

Specification of Letters Patent. Patented Sept. 14, 1920.

Application filed February 7, 1920. Serial No. 357,075.

To all whom it may concern:

Be it known that I, WILLIAM SCHNEKENBURGER, a citizen of the United States, residing at Detroit, county of Wayne, State of Michigan, have invented a certain new and useful Improvement in Weather-Strips, and declare the following to be a full, clear, and exact description of the same, such as will enable others skilled in the art to which it pertains to make and use the same, reference being had to the accompanying drawings, which form a part of this specification.

This invention relates to weather strips for windows and particularly to a weather strip designed for use at the top and bottom of a window. The object is to provide a metal strip adapted to be fastened to the window sill or the head piece of the window frame in such a manner as to engage the window sash when the windows are closed, so as to prevent rattling of the window and to keep out wind and rain which would otherwise penetrate between the window sash and frame.

25 In the drawings,—

Figure 1 is a perspective partly in cross-section showing my weather strip in place with the upper and lower windows seated.

Fig. 2 is a sectional view showing the 30 upper window sash withdrawn from the head piece of the frame.

Fig. 3 is a sectional view showing the lower window sash upraised from the sill.

Let *a* represent the window sill; *b* the 35 window jamb and *c* the head of the window frame. The sash stops for the upper and lower windows are indicated by characters *d2* and *d* respectively. The blind stop carried at the outside of the window is indicated by the letter *e*; the sash stop along the head 40 of the window frame is indicated by *h* and the stop on the window sill by *i*. The sill itself is frequently cut away to form the sash stop *i*. The same purpose, however, would 45 be served as in the case of a separate stop.

The upper window is indicated by *g*, the lower window by *f*. The cross-rail of the upper window is indicated by *g2* and the meeting rail by *g3*. The lower cross rail of 50 the lower window is indicated as *f2* and the meeting rail as *f3*. As the weather strip used for the top of the window is the same as the one used at the bottom only one will be described.

The top of the window frame serves the 55 same purpose as the sill with reference to the position of the weather strip and its method of attachment.

The sill *a* is longitudinally grooved to receive a downwardly projecting ledge *k3* 60 formed on the weather strip *k*. The weather strip then extends along the face of the sill and is provided with an upwardly projecting tongue *k2* adapted to be received in a longitudinally extending groove *l* in the 65 cross-rail of the sash. The sash stop *i* is provided with a horizontal groove *i2* adapted to receive an outwardly projecting ledge *k4* formed on the upwardly extending inner flange *k5* of the weather strip. This flange 70 *k5* is bent inwardly so that when it is engaged by the sash it will spring outwardly into the groove *i2*. This flange *k5* is formed of spring metal so that it will resistingly 75 yield outwardly as it contacts with the side of the sash and thus form a more nearly perfect weather-tight joint with the sash than would be otherwise the case.

It will be observed that the inner edge of 80 the sash is beveled so the vertical movement of the sash will not be impeded by the weather strip.

The weather strip may be formed, as shown, of one piece of metal. What has been said of the weather strip applied to the 85 bottom of the window would be equally true of its counterpart applied to the top of the window.

What I claim is:

1. In a window, the combination of a 90 window sash provided with a groove, a weather strip adapted to be attached to the window frame, said strip provided with a tongue adapted to be received in the groove in the window sash, said strip bent upwardly 95 to form a yielding flange adapted to abut the side of said sash so as to yield resistingly outwardly therefrom as the sash is seated thereagainst, said flange turned outwardly at its upper extremity to form an outwardly 100 projecting tongue adapted to be received within a groove in a window stop, said stop provided with such groove.

2. In combination with a window sill and sash adapted to be seated thereon, a metal 105 weather strip secured to the sill provided with a vertical flange adapted to be received within a groove in the sash, said strip bent

upwardly at its outer edge to provide a yielding flange inclined toward the sash adapted to be engaged thereby and yield resistsingly outward therefrom when the sash is seated on the sill, such yielding flange turned outwardly at its edge forming a tongue adapted to be received within a

groove in the outer stop, an outer stop grooved to receive said tongue, said window sash grooved to receive said vertical flange. 10

In testimony whereof, I sign this specification.

WILLIAM SCHNEKENBURGER.
